Primary Examiner—Gary D. Watson*(74) Attorney, Agent, or Firm*—Tom Hamill, Jr.(57) CLAIM

The ornamental design for the stool to be employed by baseball players, coaches, umpires and the like, as shown and described.

DESCRIPTION

FIG. 1 is a perspective view of the stool to be employed by baseball players, coaches, umpires and the like,

FIG. 2 is a top view thereof,

FIG. 3 is a front side or rear side view thereof,

FIG. 4 is a bottom view thereof; and,

FIG. 5 is a right side or left side view thereof.

The broken lines shown in FIGS. 1, 3 and 5 are for illustrative purposes only and form no part of the claimed design.
